UNITED STATES PATENT OFFICE.

CLINTON DE WITT WAGNER, OF CEDAR RAPIDS, IOWA.

ENGINE-RADIATOR.

1,381,604.

Specification of Letters Patent. Patented June 14, 1921.

Application filed April 7, 1919. Serial No. 288,071.

To all whom it may concern:

Be it known that I, CLINTON DE WITT WAGNER, a citizen of the United States, residing at Cedar Rapids, in the county of 5 Linn and State of Iowa, have invented certain new and useful Improvements in Engine-Radiators; and I do hereby declare the following to be a full, clear, and exact description of the invention, such as will enable others skilled in the art to which it appertains to make and use the same.

This invention relates to radiators for internal explosion engines, such as are used for motor vehicles; and in devising the radiator hereinafter described, three principal objects have been kept in view:

First, to produce a radiator, the core of which will not break or burst by freezing, whether once, or an indefinite number of 20 times.

Second, to simplify and expedite the repairing of radiators, by making the core of the radiator accessible. The function of the core is to radiate heat rapidly, and of 25 necessity it must be made of light material, which is always subject to injury, and must of course deteriorate with age. The radiator being an expensive part of a motor vehicle, and its material being mainly 30 non-corrosive; it should be made to do duty for many years, without extravagant costs of repairing.

Third, to produce a radiator that may be sold at a reasonable price.

The nature of the invention is fully disclosed in the description and claims following, reference being had to the accompanying drawing, in which:—

Figure 1 is a front elevation of an automobile radiator, shown conventionally, a part of the front being broken away to show the core structure within. Fig. 2 is a fragmentary view in perspective, showing details of a radiator core, various styles 45 of form-preserving tubes being illustrated in the same core, though it is to be understood they would not be generally so used. Fig. 3 shows in perspective details of a quickly detachable front and back. Fig. 4 50 shows similarly a front and back construction which admits of easy removal of the front and back, but less so than that shown in Fig. 3. Fig. 5 is an end view of one of the core tubes and part of another, connected by bracing and spacing plates as used in the preferred style of core construction.

In the drawing, the numeral 1 denotes the upper, and 2 the lower water-tanks of a radiator. These are slotted at 3 and 4, respectively to receive the upper and lower ends, respectively, of a series of thin and wide tubes, which, for distinction are numbered 5 and 6. In practice these tubes are preferably made of thin brass or copper 65 folded on itself with an overlapping, soldered seam 8 at the back of the radiator. Provision is made for holding the walls of the tube normally parallel, or substantially so, and for bringing to bear on a side wall 70 a pressure tending to force the wall inwardly. Such a tube, when frozen, will expand in thickness, and contract very slightly edgewise. When thawed out the tube will at once resume its normal position.

Taking for example the preferred form of tube, 5, the sheet of soft brass or copper, before folding at the edges, is corrugated at 10 for a threefold purpose: It forms a 80 groove to receive a longitudinal stiffening wire 11; it is in itself a stiffener; and it forms an abutment at the inside of the tube to hold its walls in proper normal position, practically parallel. In practice, a 85 pair of these corrugations and stiffening wires is preferred instead of a single one, as indicated above. The beads or corrugations do not increase the resistance of the tube walls against expansion, but do stiffen 90 it endwise, so that pressure from within, brought to bear at any point, is transmitted for a considerable distance each way therefrom longitudinally. This effect is of course enhanced by the use of the wires, which 95 may be practically straight when laid in the grooves, where they are securely attached by soldering. Over these wires, at intervals along the length of the tube, are secured clips 12, formed of somewhat elastic material, preferably what is commonly known as "half hard" brass. This usually comes in rolled strips of suitable width, and the cut lengths are given reverse bends 13, at the ends to overlie 100 the edges of the tube, as clearly shown in Fig. 5, the bend at the front edge being preferably a hook, so as to dispense with solder, though at the opposite end the clip is securely soldered to the tube. It is evi- 110

dent that the natural bulge of the clip will thus tend to press inwardly on the underlying wall of the tube, and so hold it in proper position. If now the water in the tube should be frozen, the tube would of course be bulged outwardly a little, but as soon as the ice thawed the tube would automatically return to normal position, so that any number of freezings and thawings would not change its proper form. The same is true of a bulging caused by steam in the radiator due to a stoppage in the overflow pipe and a tight nozzle cap, though the expansion in such a case is more apt to effect the upper water tank than the core tubes.

It is to be understood that I do not regard the stiffening wires as absolutely indispensable and have shown tubes 6 without such wires. I consider the wires a useful adjunct, however, as above noted.

The tubes are securely soldered in the slots of the upper and lower water-tanks, but this alone would leave the radiator core as a whole inadequately stiffened and braced. Accordingly the tubes are set in alternately reversed position, with clipped walls and plane walls facing each other, respectively. The plane walls of adjoining tubes are securely tied together with angled strips of perforated sheet metal 14, soldered to such tubes, and serving to truss them and the whole radiator core, and render it rigid, especially against diagonal strains. The perforated strips permit the free passage of air through the radiator, and enlarge the radiating surface of the radiator core, as will be evident. Painted the same color as the radiator front they also serve for concealment of the brass tubes, which are preferably not painted. For this purpose of screening the interior of the radiator, alternate strips of perforated sheet metal 15 may be set between the elastic walls of the tubes, but not attached to them, nor indeed touching them, except at points 16, where the back edges are outturned a little, and stuck to the tubes with a drop of solder. To make the screen strips a little yielding, they should be U-shaped in cross-section, as indicated by the outline of the lower end in Fig. 2. Where this matter of concealment is not important the screen-strips may be dispensed with.

Improved fronts 17 and backs 18 are shown in Figs. 3 and 4. In the latter, the fronts and backs are simply beaded at 19 to receive the edges of the intervening tubes, which may be soldered directly to such front and back plates. In Fig. 3 is shown a construction of the front and back requiring no soldering of them to the tubes. Inside the front and back plates are secured transverse bars 20, suitably notched at 21 to engage the curved clip-ends, and through these pass

bolts 22, one of which is shown, and by means of which they are securely clamped to the radiator core.

The tubes are placed near enough together to secure adequate radiation, but with space 70 between for a small soldering copper, or a torch flame. To repair the radiator is a simple operation for any tinsmith. Most leaks occur at the back side of the radiator, the end tubes being the most subject 75 to injury or impairment. For this reason the terminal tubes should preferably be made of heavier material than the others. If a tube is leaking, the back is easily removed by melting the few points of attachment, if 80 soldered to the tubes, or by unbolting, if of the type shown in Fig. 3. Access is had immediately to the leaking tube, and the repair is easily made. If the leak is at the front side, the front is as easily and quickly 85 removed, or, if the leak be at the side of the tube, the same may be repaired from the back side. If from age and service the tube has become thin and rotten, it is easily snipped off at the top and bottom, the stub ends 90 melted out of the tanks, and a new tube inserted. In this there is no mutilation of the front or back, and when replaced and repainted, if paint has been injured by heat, the radiator shows no injury whatever. The 95 removal of a tube of course involves the removal of the angled stiffening strips, but this is a very simple operation, either with a torch or a hot copper.

In this invention the tube, individually 100 considered, is an element of primary importance. Its leading characteristic is a tendency to bulge or buckle inwardly and transversely. To this is added means for holding the walls normally distended. Other means 105 serve to transmit the buckle of the flexible wall endwise of the tube in approximate parallelism.

It is to be noted that the inward buckle of the elastic wall is due to means forming a 110 component part of the tube, not wearing frictionally thereon, nor liable to disconnection therefrom, and with no possibility of rattle or vibration in the running of the vehicle to which the radiator is attached.

In Fig. 5 the dimensions of the parts are approximately the actual size as manufactured, but for convenience of illustration the thickness of the metal indicated is greatly exaggerated.

A superadded feature, not inherent in the tube itself, but designed to greatly strengthen it and prolong its life and efficiency, is the stiffening strip, giving rigidity to one side of the tube, and correspondingly to the 125 whole radiator core.

Having thus described my invention, I claim:

1. A radiator tube having wide, narrowly separated and practically parallel walls, and 130

elastic means embracing the edges of the tube, and tending to collapse the tube intermediate its edges.

2. A radiator tube having wide, narrowly separated and practically parallel walls, and a series of springs embracing the edges of the tube, and tending to press its walls back to normal position when distended.

3. A radiator tube, having wide, narrowly separated walls, means disposed transversely of the tube to press a wall inwardly, and means disposed lengthwise of the same wall to stiffen it in that direction.

4. A radiator tube, having wide, substantially parallel, and narrowly separated walls, means disposed crosswise of the tube to press it inwardly, and a stiffening bead formed lengthwise of said wall, and adapted to hold the walls properly separated.

5. A radiator tube, having wide, substantially parallel and narrowly separated walls, elastic means disposed crosswise of the tube and tending to press it inwardly, a longitudinal bead formed in said wall, and a stiffening wire set therein.

6. In a radiator, a pair of tubes, having wide, narrowly separated walls, perforated stiffening strips attached rigidly to the opposing walls of the pair, and means transversely disposed on the outer walls tending to press them inwardly and elastically.

7. In a radiator, the combination of a

series of wide, thin tubes, water-tanks connecting with their ends, means for pressing the opposing walls of a pair of said tubes inwardly, means to hold the walls properly separated, and perforated, stiffening strips connecting alternate pairs of said tubes to each other and to the tanks.

8. In a radiator, the combination of a series of wide, thin tubes, water tanks connecting with their ends, elastic means tending to press inwardly the opposite walls of pairs of said tubes, perforated stiffening strips rigidly connecting alternate pairs, to render one wall of each tube rigid, and perforated, screen-strips disposed between the elastic walls of the tubes, and mainly separated a short distance therefrom.

9. In a radiator, the combination with upper and lower water-tanks, of wide, thin connecting tubes, provided with elastic, inwardly pressing spring clips overlapping the edges of said tubes, bars grooved to fit said overlapping portion of clips, binding bolts therefor, and perforated front and back plates attached to said bars.

In testimony whereof I affix my signature in presence of two witnesses.

CLINTON DE WITT WAGNER.
